Application filed December 20, 1900. Serial No. 40,605. Term of patent 3½ years.

To all whom it may concern:

Be it known that I, ALFRED C. ABRAMSON, a citizen of the United States, residing at Rockford, in the county of Winnebago and 5 State of Illinois, have invented and produced a new and original Design for Sewing-Machine Cabinets; and I do hereby declare the following to be a full, clear, and exact description of the same, reference being had to the accompanying drawing, forming a part thereof.

The accompanying drawing is a perspective view of the new design for sewing-machine cabinets.

The design consists in a cabinet substantially of the configuration shown.

The cabinet comprises the ends 1, front in two sections 2 and 3, divided by a center column 4, outside columns 5 and 6, top 7,

supplemental top 8, having the railing 9, and the portions 10 between the top and the upper portion of the sections 2 and 3. The sections have the fanciful ribbon-like ornate- 20 tations 11.
